2,037,923

METHOD OF CLOSING METAL CONTAINERS

William F. Punte, Syracuse, N. Y., assignor to
 Continental Can Company, Inc., New York,
 N. Y., a corporation of New York

Original application May 23, 1932, Serial No.
 613,094. Divided and this application March
 19, 1935, Serial No. 11,852

1 Claim. (Cl. 113—121)

The present invention relates to new and useful improvements in a method of closing metal containers and more particularly to a method of closing metal containers of the type wherein the cover is secured to the container body by a sealing ring and wherein a sealing gasket is disposed between the cover and the body portion.

An object of the invention is to provide a method of closing a container of the sealing ring type wherein the pressure applied to the sealing ring for deforming the same and sealing the container may be utilized for firmly pressing the cover into sealing contact with the gasket and for firmly pressing the gasket into sealing contact with the container body simultaneously with the deformation of the sealing ring.

The above and other objects of the invention will in part be obvious and will in part be herein-after more fully disclosed.

20 In the drawing:

Fig. 1 is a side elevation partly in section showing a metal container of the type referred to.

Fig. 2 is a fragmentary plan view of the same.

Fig. 3 is an enlarged fragmentary vertical section through the container and sealing ring showing the parts assembled prior to the application of the sealing ring to die pressure.

Fig. 4 is a view similar to Fig. 3, but showing the sealing ring after pressure has been applied for closing the container.

It is believed that the improved method of closing a sealing ring container will be better understood if such a container ready for closing by the improved method is first described in detail.

The container as illustrated in the accompanying drawing consists of a body portion 1 which is preferably cylindrical and a closing bottom end 2 which is secured to the body portion by double seaming. The upper end of the container body is provided with an inturned hollow bead 3 and an annular depression 4 spaced from the bead 3. The annular depression 4 is shaped to provide a substantially horizontal holding shoulder 5. The formation of this annular depression produces a container wherein both ends are of substantially the same diameter, and yet there is provided a locking or holding shoulder 5. The container is closed by a cover 6 which is in the form of a disc extending across the open end of the container and having a depending flange 7. This flange extends downwardly over the body wall of the container engaging the same so as to provide a frictional closure. This arrangement of parts produces a

cover which may be used for reclosing the container after the sealing ring is removed. The cover flange 7 is bent outwardly at the upper edge thereof as at 8 and the closed portion of the cover is curved upwardly as at 9 in order to form a channel or recess above the hollow bead 3 for the sealing material which is in the form of a sealing gasket 10. The lower edge of the cover flange 7 is bent outwardly and then inwardly to form a half bead 11, the inner face of which is substantially in line with the inner face of the flange. The half bead 11 terminates adjacent but slightly above the holding shoulder 5. This bead at the lower end of the cover flange serves to place the sharp edge thereof adjacent the body whereby to prevent any danger of cutting the hands in removing the sealing material. It also forms a substantial support for the lower portion of the sealing ring to bear against when it is pressed into locking position and thus maintains the wall of the sealing ring substantially parallel with the upper section of the body wall.

The cover is secured to the container body by sealing ring 12 which has overlapping ends, one of which is indicated at 13. The upper portion 25 of the sealing ring is bent inwardly as at 14 and overlies the curved portions 8 and 9 of the cover. This bent portion of the sealing ring is curved inwardly and downwardly about a shorter radius than the curved portion 9 of the cover section. 30 The inner edge of this bent portion 14 contacts with the curved portion 9 of the cover, when applied thereto, at a point well beyond the crown of the curved portion. The sealing ring 12 is also provided with an inwardly projecting portion 12a at its lower edge which is curved inwardly and upwardly.

The above described container forms no part of the present invention, but is shown and described in the copending application of William F. Punte, Serial No. 613,094, filed May 23, 1932, of which this application is a division.

In carrying out the invention, the parts are first assembled as shown in Fig. 3. With the parts thus assembled, that is, with the upper portion 14 of the sealing ring overlying the cover 6 and with the lower portion 12a of the sealing ring disposed beneath the holding shoulder 5, the container is subjected to a closing apparatus in the form of die members, one of which is indicated at x and the other at y. These die members x and y are then moved relatively toward each other. The die member x will contact with the inwardly projecting portion 12a of the sealing ring, while the die member y will contact

with the curved upper portion 14 of the sealing ring. As these die members move toward each other, the sealing ring 12 will be deformed or shortened in a direction parallel with the side wall of the container wall. The die member *y* has a curved contact surface which corresponds to the final curvature given to the edge portion 14 of the sealing ring. This curved portion 14, which contacts with the cover at a point directly over the inside of the hollow bead 3 on the container body, will be moved inwardly and changed in shape so as to conform more nearly to the curvature of the portion 9 of the cover as shown in Fig. 4. The lower edge 12a of the sealing ring 15 will be straightened out beneath the holding shoulder 5 as indicated in Fig. 4. This shortening of the side wall of the sealing ring 12 is accomplished by pressure applied in a direction parallel with the side wall of the container body. 20 This pressure is also transmitted against the shoulder 5 and against the cover, thus tending to move the cover toward the shoulder. This movement will cause the cover to make a very intimate sealing contact with the sealing gasket 10, which in turn will be caused to make a very intimate sealing contact with the hollow bead 3 on the container body. The die members *x* and *y* include the usual spring means which will only yield when a seal of proper tightness is obtained, 30 and therefore, as the die members move toward each other, the sealing gasket 10 will be pressed against the bead 3 and it is only the tightness of the seal which will prevent further movement of the die members relative to each other. 35 The finally closed container is, as noted above, shown in Fig. 4. The sealing gasket 10 has been forced into intimate contact with the bead 3 and into the recess formed between the outer curved portion of the bead and the curved portion 8 of the cover. There is thus formed a tight contact of the sealing gasket with the cover all the way to the inner side of the bead, and there is also formed a tight sealing contact with the bead throughout the upper surface thereof. The 40 metal of the sealing ring is non-elastic, so that, as pressure is applied thereto and the cover is forced into tight sealing contact with the container body, the changing of the shape of the sealing ring will remain in the final shape given thereto by the pressure of the dies. The expansion of the gasket 10 is thus limited by the

upper and lower portions 14 and 12a respectively of the sealing ring, and therefore the cover will be held in tight sealing contact with the gasket, and the gasket in tight sealing contact with the bead 3 through this deformation of the sealing 5 ring 12.

It is understood that the cover and sealing ring are applied to the container by the manufacturer, and that the container, after it is filled by the packer, has the bottom end 2 double seamed 10 hereto.

While the invention has been described as applied to the closing of the container shown in detail in the accompanying drawing, that is, one wherein a sealing ring is deformed by pressure to 15 firmly hold the cover in tight sealing engagement with the container body, it will be understood that it may be used in connection with containers of other types. It is essential, however, that the container shall be so constructed that pressure may 20 be applied to a metal part in a direction parallel with the body wall of the container, so that this pressure may be utilized for firmly pressing the cover against the gasket and the gasket against the container body during the deformation of 25 the metal part so that a tight seal is thus obtained.

Having thus described the invention, what I claim as new and desire to secure by Letters Patent, is:—

A method of closing containers consisting in shaping the body of the container so as to provide a rolled bead at the upper edge thereof and a shoulder located beneath said bead, applying thereto a closure having a sealing gasket on its inner face, which closure is curved directly above said bead so as to overlie said bead for compressing the gasket against the bead, applying to said closure and container body a clamping ring having an inwardly extending flange at its upper 40 edge normally curved about a shorter radius than the curvature of the closure so that the inner edge of said flange contacts only with said closure, which clamping ring also is provided with an inwardly projecting curved flange at its lower 45 edge adapted to overlie said shoulder on the container body, applying pressure to the flanges of the clamping ring in a direction parallel with the body wall for deforming the flanges and clamping the closure to the container body. 50
